UNITED STATES PATENT OFFICE.

FORREST L. BRISSEY, OF OAKLAND, CALIFORNIA.

AMUSEMENT DEVICE.

Application filed March 1, 1921. Serial No. 448,780.

To all whom it may concern:

Be it known that I, FORREST L. BRISSEY, a citizen of the United States, residing at Oakland, in the county of Alameda and State of California, have invented new and useful Improvements in Amusement Devices, of which the following is a specification.

My invention, while relating in general to amusement devices, has particular reference to an improved puppet show, which in its preferred form includes in combination, a suitable miniature stage, with its usual accouterments, and a plurality of marionettes, each of which is capable of producing animated exhibitions upon the stage, to simulate various performances.

I am aware that several attempts have been made to produce devices of this character but the same have fallen short of providing realistic exhibitions owing primarily to the unsatisfactory arrangements for accommodating the marionettes on the stage and the manipulation of the same by the puppet man.

Having in mind overcoming the defects experienced with these former devices, I propose to provide a comparatively simple and cheap device as well as one which will operate with the greatest of efficiency, not only from a realistic point of view but also so far as concerns simplicity of manipulation.

One of the important features of my improved arrangement resides in a construction with which a variety of spectacular animated performers may be exhibited through the medium of the marionettes capable of being used either selectively or collectively, according to the nature of the performance. With this end in view, I have so produced the different sets of marionettes, that each one in itself becomes a unit, with the stage made to accommodate either a single unit or a group of them and with the controls adapted to be actuated at will according to the effects to be realized.

In the accompanying drawings forming a part of this specification and in which like numerals are employed to designate like parts throughout the same, I have selected for the purpose of illustration a preferred form of stage and two different marionette

units, which will illustrate the salient features of the invention.

Figure 1 is front elevation of the stage with one of the marionette units exhibited thereon.

Figure 2 is a top plan view of the stage.

Figure 3 is a vertical section on the line 3—3 of Figure 1, and,

Figure 4 is a detail view in front elevation showing the application of one of the marionette units, and

Figure 5 is a detail view of one of the control cords for the units.

Referring now to the drawings in detail, I prefer to produce the stage from a suitable framework including at least two front and two rear uprights A, each two being spaced apart by the upper horizontal bridge pieces B, extending from front to the rear of the stage, with an upper longitudinal member C joined to the rear of the bridge pieces B. The lower part of the frame is braced by the stage floor D which joins the uprights A above the lower ends thereof and extends forward of the stage front to accommodate a foot light form E. The back of the frame may be covered with card board or the like F printed or painted to represent the back of a theatre building. The front of the frame may be covered with card board or the like G, but the same should simulate the architecture of a theatre stage by painting or otherwise displaying columns or the like designs on the front of the card board. The center of the front card board should be cut out to leave an unobstructed view to the stage.

In order to give a proper appearance to the stage, it is proposed to use at least two curtains 5 and 6, each of which being of a length and width to cover the opening into the stage, and the same are preferably wound upon separate spindles 5' and 6'. The spindle 5' for the curtains 5 is preferably supported with freedom of rotation between the two front uprights A, slots being cut in the uprights to provide bearings for the spindle 5' and the spindle for the curtain 6 is preferably supported with freedom of rotation between the horizontal bridge pieces B, slots being also cut in these pieces to provide bearings for the spindles 6'.

Suitable wings 7, also made of card board

or the like may be employed on each side of the stage opening the same, cut and painted or otherwise made to appear as columns or draperies.

5 Each of the curtains may be pulled down or up by separate pull cords wound upon the spool ends 5 and 6 of the spindles.

To make up the different settings the background of the stage may be changed at will 10 by means of suitably painted or printed drops 8. Any number of such drops may be on hand to correspond to different exhibitions to be given by the marionettes and the same may be conveniently suspended 15 from the horizontal bridge pieces B by leaving an over hang or extension 9 at opposite sides of their top edge as best shown in Figures 2 and 3.

As previously stated each of the marionette sets will include a unit complete in itself 20 and the units may be used singly or in groups, for instance, for the purpose of illustration. I have shown two different marionettes or puppets each being capable of producing different exhibitions when properly 25 manipulated or prompted by the puppet-man. Considering first the marionette 10, it is to be noted that the same is made to represent a clown, the figure being produced 30 preferably from card board and supported by a suitable base 10'. In this case the clown is positioned on the stage in side view to the audience and one of its arms is pivoted as at 10² with a spring adapted to normally 35 hold the arm down so that the pointer 10³ will point to the floor. The pull control cord 11 may be used to raise the arm and thus produce the desired animated effect.

As heretofore practiced in devices of this 40 kind the puppet-man usually actuated the pull cords from in back of the stage but this position does not appear as real as is desired. I therefore have devised means by which the cords may be actuated beneath the 45 stage which removes the cords from view. To accomplish this the stage floor is provided with small openings 12 at places where the marionette sets are to be positioned and with the bases of the sets also provided with 50 an opening so that the control or pull cords may be passed under the stage where they may be actuated.

In Figure 4 I have shown a rather elaborate form of marionette set, yet, considering 55 the exhibition it is capable of displaying, it is comparatively simple. In this form the marionette or puppet 13 is produced to represent an acrobat or tight rope walker and the unit set of which it forms a part includes 60 a supporting base 13', the same being of a length of substantially that of the width of the stage. At each end of the base is arranged an upright 13² which forms a support for the guide wire 13³ and the tight 65 rope 13⁴, the former acting as a guide for

the marionette 13 and the latter representing the wire on which the marionette walks. 14 represents a platform which is supposed to represent the stand from which the tight rope walker ascends the rope.

The pull or control cord 15 in this set extends through openings in the uprights and is fixed to the marionette so that a pull on either of its ends which extend through the 70 openings in the base and stage floor to beneath the stage will cause the marionette to travel across the stage with the appearance 75 as if it were walking the wire 13⁴.

In exhibiting this form of marionette, a very dark drop 8 is used to provide a black 80 back ground which will hide the wire 13³ and the pull cord 15 these two being black themselves. The wire 13⁴ as well as the coloring of the marionette should of course 85 be either white or at least some light color so they will stand out against the back ground.

Practically the same principle would apply if it were desirable to simulate an illusion, such for instance as practiced by 90 magicians in supporting objects in space.

The pull cords or control cords may each have a threading needle on their free ends so that the cords may be threaded through 95 the openings in the bases and the openings in the stage floor.

It is to be understood that the form of my invention herewith shown and described, is to be taken as a preferred example of the 100 same, and that various changes in the shape, size and arrangement of parts may be resorted to without departing from the spirit of the invention, or the scope of the subjoined claims.

Having thus described my invention, I 105 claim:—

1. An amusement device comprising in combination a stage, and a marionette set, a supporting base for the marionette set having an opening therein the stage floor having an opening therein adjacent which the marionette set may be positioned for exhibiting purposes adapted to register with the opening in the supporting base of the marionette set, and a control cord for the 115 marionette extending through said openings, whereby the marionette may be attached by said cord from the under side of the stage.

2. An amusement device comprising in 120 combination a stage and a marionette set, the marionette set including a base, parallel wires supported above said base, one above the other, the higher wire suspending the marionette with the same free to slide thereon, the lower wire appearing as a support for the marionette and a pull cord for moving the marionette along the higher wire.

3. An amusement device comprising in 130

combination a stage and a marionette set, the marionette set including a base, parallel wires supported above said base one above the other, the higher wire suspending the 5 marionette with the same free to slide thereon, the lower wire appearing as a support for the marionette and a pull cord for moving the higher wire and a back ground for the stage behind the marionette set 10 adapted to obliterate the higher wire and the pull cord but bringing out the appearance of the marionette and the lower wire.

4. An amusement device comprising in combination a stage and a marionette set, 15 the marionette set including a base, parallel wires supported above said base one above the other, the higher wire suspending the marionette with the same free to slide thereon, the lower wire appearing as a support 20 for the marionette, the stage floor having an opening therein adjacent which the marionette set may be positioned, a pull cord for moving the higher wire and extending through the opening in the stage floor

whereby the marionette may be actuated 25 from below the stage floor.

5. An amusement device comprising in combination a stage and a marionette set, the marionette set including a base, parallel wires supported above said base, one above 30 the other, the higher wire suspending the marionette with the same free to slide thereon, the lower wire appearing as a support for the marionette, the stage floor having an opening therein adjacent which the marionette set may be positioned, a pull cord for moving the higher wire and extending 35 through the opening in the stage floor whereby the marionette may be actuated from below the stage floor and a back ground for the 40 stage behind the marionette set adapted to obliterate the higher wire and the pullcord but bringing out the appearance of marionette and the lower wire.

In testimony whereof I affix my signature. 45

FORREST L. BRISSEY.
